UNITED STATES PATENT OFFICE.

ADOLPHE M. BURTON, OF BALTIMORE, MARYLAND.

DESIGN FOR A TOY DOG.

59,578.

Specification for Design.

Patented Nov. 8, 1921.

Application filed April 1, 1921. Serial No. 457,829. Term of patent 14 years.

To all whom it may concern:

Be it known that I, ADOLPHE M. BURTON, a citizen of the United States, residing at Baltimore, in the county of Baltimore and State of Maryland, have invented a new, original, and ornamental Design for a Toy Dog, of which the following is a specification, reference being had to the accompanying drawing, forming part thereof.

The figure is a perspective view of the toy dog, showing my new design.

I claim:

The ornamental design for a toy dog, as shown.

ADOLPHE M. BURTON.
